UNITED STATES PATENT OFFICE.

JACOB J. THELEN, OF SCHENECTADY, NEW YORK, ASSIGNEE OF ONE-HALF TO HARRY G. HOGAN, OF SCHENECTADY, NEW YORK.

CHECK-VALVE.

1,072,673.

Specification of Letters Patent.

Patented Sept. 9, 1913.

Application filed March 2, 1912. Serial No. 681,027.

To all whom it may concern:

Be it known that I, JACOB J. THELEN, a citizen of the United States residing at Schenectady, in the county of Schenectady 5 and State of New York, have invented certain new and useful Improvements in Check-Valves, of which the following is a specification, reference being had to the accompanying drawings.

10 My invention relates to new and useful improvements in check valves and my object is to provide a device of this character which is simple in construction, inexpensive to manufacture and one which is very efficient 15 in operation.

A further object of the invention resides in providing a device which is so constructed as to be readily taken apart for repairs or other purposes when desired.

20 With these and other objects in view, my invention consists in the novel features of construction, combination and arrangement of parts as will be hereinafter referred to and more particularly pointed out in the 25 specification and claim.

In the accompanying drawing forming a part of this application, Figure 1 is a vertical section through the device; and Fig. 2 is a horizontal section therethrough, as seen 30 on line 2—2 of Fig. 1.

In describing my invention, I shall refer to the drawing in which similar reference characters designate corresponding parts throughout the several views and in which 1

35 indicates a valve body or casing having the inlet 2 provided in the bottom thereof adapted to receive a pipe, not shown, said casing or body being also provided with a valve seat 3.

40 A disk valve 4 is adapted to be seated on the valve seat 3, said disk being formed integral with a stem or shank 5 extending above and below the same. That portion of the stem or shank which extends below the disk is of a smaller diameter than the

45 upwardly extending portion of the shank and the same is slidably disposed through a guide sleeve 6 formed in a spider 7, which is disposed in the inlet of the member 1 between the extreme lower portion thereof and said valve seat 3. It will be observed that the seat 3 is projected inwardly into the casing, thereby forming an annular trough 3' surrounding said seat.

50 The upper portion of top of the casing or body 1 has an outlet opening 8 therein the

walls of which are threaded to receive in engagement the threaded lower portion of a union or cap member 9, said member 9 being adapted to receive therein the end of a pipe, not shown. This union or cap member 60 9 has a spider or the like 10 formed in the bottom thereof which supports an additional guide sleeve 11 which is disposed in alignment with the guide sleeve 6 and adapted to receive therethrough the upwardly projecting portion of the shank 5, formed on said valve. The valve therefor will be guided throughout its movement when raised and lowered.

65 As stated, the valve 4 is of disk-like formation, the upper face of the same being somewhat convexed, while the bottom face of the same is flat and provided with an annular groove 12 contiguous with the downwardly projecting portion of the shank 75 5. Any back pressure whatsoever after the valve has been raised will cause the latter to return to its effective position on the seat 3, and as the projecting portions of the shank 5 are normally disposed through the 80 guiding sleeves 6 and 11, it will be appreciated that said valve will be guided throughout its movement. By the provision of the annular trough 3', the valve seat is raised so that sediment will not collect 85 thereon but will settle below the valve into said trough, and thus materially lessen resistance to the flow past the valve.

90 From the foregoing, it will be seen that I have provided a check valve which is simple and durable in construction, inexpensive to manufacture, and one which is very efficient in operation.

95 While I have particularly described the elements most well adapted to perform the functions set forth, it will be understood that the invention is capable of various changes and modifications within the scope of the appended claim.

100 In order to limit the upward movement of the stem or shank 5 so as to prevent total displacement of the same when raised, a collar 12' is formed on the upwardly extending portion of said shank which is adapted to abut the lower edge of the guide sleeve 11 when the disk 4 is raised.

105 Having thus described this invention, what is claimed is:—

110 The herein-described check valve comprising a casing having inlet and outlet ports

and a valve seat projecting into the casing around said inlet port and providing an annular trough surrounding said seat, a valve member comprising a stem having a 5 valve disk integrally formed thereon intermediate of its ends, said disk being of greater diameter than the valve seat to overhang said annular trough when engaged upon said seat, the under surface of said 10 valve disk being flat and provided with an annular groove contiguous to the valve stem

and of less diameter than the valve seat, the upper surface of said valve disk being convex, and means arranged in the inlet and outlet ports for guiding the valve stem in 15 its movement.

In testimony whereof I hereunto affix my signature in the presence of two witnesses.

JACOB J. THELEN.
